Nelson W. Howard

UNITED STATES PATENT OFFICE.

JOSEPH BRUNELL, OF BROOKLYN, NEW YORK, ASSIGNEE TO UNITED SHOE MACHINERY CORPORATION, OF PATERSON, NEW JERSEY, A CORPORATION OF NEW JERSEY.

METHOD FOR USE IN THE MANUFACTURE OF SHOES.

1,418,359.

Specification of Letters Patent. Patented June 6, 1922.

Application filed July 28, 1921. Serial No. 488,194.

To all whom it may concern:

Be it known that I, JOSEPH BRUNELL, a citizen of the United States, residing at Brooklyn, Kings County, State of New York, have invented certain Improvements in Methods for Use in the Manufacture of Shoes, of which the following description, in connection with the accompanying drawings, is a specification, like reference characters on the drawings indicating like parts in the several figures.

This invention relates to methods of making shoes and particularly to methods of retaining the uppers of shoes in proper position during shoemaking operations such as lasting, the method being of special utility in connection with lasting the uppers of pumps or slippers.

In the case of a high or Oxford shoe the upper is, of course, supported by the buttons or lacing flies which are fastened together over the instep before they are assembled on a last. In shoes of the pump or slipper type, however, there is no such support for the upper since no part of the upper extends over the instep and hence in lasting the upper of such a shoe over its last it is desirable temporarily, during the lasting operation, to hold the upper in the proper position which it should occupy on the last. It is undesirable to fasten the upper of a pump to the last by tacks inserted through the upper and into the last to hold it in place since such a procedure would result in injury to the delicate material of which such uppers are usually made.

Objects of the present invention are to provide a method of holding in place the upper of a shoe in proper relation to the last during operations such as lasting which tend to displace the upper on the last, and to provide a method which, while permitting tacks to be used as the actual means for holding the upper to the last, does not result in injury to the upper or encumber the shoe when finished with any extra material.

With these objects in view the method is carried out as herein illustrated by securing to the upper, preferably to the inner layer or lining, a piece of leather or other suitable material, by means which may be readily

torn or raveled, in such a position that a portion of the piece projects or is exposed above the line of the upper on the last. These pieces of material may be appropriately referred to as "detachable tabs." An upper provided with detachable tabs is assembled on its last in proper position and the exposed portions of the tabs secured to the last by suitable means such as tacks. The upper is then subjected to the usual shoemaking operations, such as lasting, by which the margin of the upper is worked over the last bottom and secured, and if the shoe is a welt shoe the usual inseaming, trimming, filling and sole attaching operations including, if desired, the attachment of a heel, may be carried out before the shoe is removed from the last. When the operations upon the shoe have advanced to the point where it is necessary to remove the last from the shoe the tacks holding the tabs to the last are removed and the last pulled. The tabs are then removed from the upper by tearing them off when, for instance, the tabs are secured to the upper by a seam of weak thread, or by raveling out the seam as may be readily done if the tabs are secured to the upper by a chain-stitch seam. The pieces or tabs may be employed again and again upon different uppers until they are worn out.

In the drawing—

Fig. 1 represents in perspective an upper prepared for lasting in accordance with the present invention.

Fig. 2 is an enlarged cross-section on the line 2—2 of Fig. 1, and

Fig. 3 represents in side elevation a shoe upper attached to a last in accordance with the present invention, the shoe having been lasted and welted.

In the practice of the present invention suitable pieces or tabs 2, 4 are prepared, preferably of scraps of leather or fabric which are of little use for any other purpose. During the operations of sewing together parts of the upper in the stitching room two of these tabs are sewed one on each side of the upper 6 and, preferably to the inner layer or lining 8 of the upper only by a seam 10 in such location that when the upper is assembled upon its last the tabs will

extend along each side of the upper between the ball line and heel breast line and will project above the top line 12 of the upper a convenient distance. In sewing on the tabs a relatively weak thread may be used so that after the tabs have served their purpose they may be readily ripped off. Another very convenient way of detachably securing the tabs is to employ a chain-stitch, as shown in Fig. 1, so that the tabs may be removed simply by pulling on the proper loose end 14 of the thread. By this method no trace of the securing means remains in the shoe after the seam is unraveled and also a stronger thread may be employed and greater holding power of the tabs secured than is practicable when the tabs are secured by a seam which is to be ripped.

After the tabs have been secured to the upper as described other necessary operations may be performed to prepare the shoe to receive the last. The upper is then assembled upon the last with the back seam and side lines of the upper in proper relation to the last and a few tacks 16 driven through the exposed portion of the tabs extending above the top line 12 of the upper and into the last. The upper is then lasted in any usual manner. During the lasting of the sides of the upper the tabs 2, 4, held to the last by the tacks 16, serve to hold the top line of the upper in the position in which it has been secured and prevent displacement of the top line of the upper when the upper is put under strain by lasting pincers or other lasting instrumentalities. After the upper is lasted the shoe may be completed in the usual manner, for instance, by weltting, filling, attaching the outsole, and heel-ing, or only such of these operations as are to be performed with the shoe on the last may be carried out. Then the lasting tacks 16 are removed and the last pulled out. At any time after the last is pulled the tabs may be removed either by ripping the seam by which they are held to the upper or by unraveling the seam, in case it is formed by a chain-stitch, by pulling the unlocked end 14 of the thread. Preferably the tabs are saved after removal and sent back to the stitching room to be used again for the same purpose in other uppers.

By this method it is possible properly to last the sides of a shoe upper and to draw the upper to the wood in the shank without danger of displacing the top edge of the upper and destroying the lines of the shoe. Moreover, a shoe thus lasted will hold better to the foot and will not bulge away from the foot when worn, thus insuring better appearance, longer wearing qualities and more comfort to the wearer. These results are highly desirable, particularly in a pump in which the fitting of the top line to the wear-

er's foot is depended upon to hold the shoe upon the foot.

Having thus described my invention, what I claim as new and desire to secure by Letters Patent of the United States is:

1. That improvement in methods of making shoes which consists in attaching tabs to an upper, assembling the upper upon a last, attaching the tabs to the last to maintain the upper in position on the last, performing shoemaking operations, detaching the tabs from the last, removing the last, and finally detaching the tabs from the upper.

2. That improvement in methods of making shoes which consists in attaching tabs to the upper on opposite sides of the shoe in position to extend above the top line of the upper, assembling the upper upon a last, attaching the tabs to the last to maintain the position of the top line, lasting the shoe, detaching the tabs from the last, removing the last, and finally detaching the tabs from the upper.

3. That improvement in methods of making shoes which consists in chain-stitching tabs to the upper on opposite sides of the shoe, assembling the upper upon a last, attaching the tabs to the last to maintain the position of the top line, lasting the shoe, detaching the tabs from the last, removing the last, and finally unraveling the chain-stitches to permit removal of the tabs from the upper.

4. That improvement in methods of making shoes which consists in sewing to the upper upon opposite sides of the shoe pieces of material in position to be exposed above the top line of the upper, assembling the upper upon a last, securing the exposed portions of the pieces to the last so as to prevent the upper from being displaced by the strain of lasting the upper, then lasting the upper, detaching the tabs from the last, removing the last, and destroying the seam which holds the pieces to the upper.

5. That improvement in methods of making shoes which consists in sewing to the lining or inner layer of the upper upon opposite sides of the shoe pieces of material in position to be exposed above the top line of the upper, assembling the upper upon a last, securing the exposed portions of the pieces to the last so as to prevent the upper from being displaced by the strain of lasting the upper, then lasting the upper, detaching the tabs from the last, removing the last, and destroying the seam which holds the pieces to the upper to permit removal of the pieces.

6. That improvement in methods of making shoes which consists in sewing pieces of material by chain-stitch seam to the upper upon opposite sides of the shoe in position to be exposed above the top line of the up-

per, assembling the upper upon a last, securing the exposed portions of the pieces to the last so as to prevent the upper from being displaced by the strain of lasting the upper, then lasting the upper, detaching the tabs from the last, removing the last, and raveling the seam which holds the pieces

to the upper by pulling upon the unlocked end of the thread forming the chain-stitch seam.

In testimony whereof I have signed my name to this specification.

JOSEPH BRUNELL.

10

Certificate of Correction.

It is hereby certified that in Letters Patent No. 1,418,359, granted June 6, 1922, upon the application of Joseph H. Brumell, of Brooklyn, New York, for an improvement in "Methods for Use in the Manufacture of Shoes," an error appears in the printed specification requiring correction as follows: Page 2, line 120, claim 5, for the word "displayed" read *displaced*; and that the said Letters Patent should be read with this correction therein that the same may conform to the record of the case in the Patent Office.

Signed and sealed this 11th day of July, A. D., 1922.

• [SEAL.]

KARL FENNING,

Acting Commissioner of Patents.
